33rd Anaconda and A. Oliver
his Attorney,

UNITED STATES PATENT OFFICE.

EDWIN M. WINTERBOURNE, OF TRINIDAD, COLORADO.

KITCHEN WORK-STOOL.

1,319,258.

Specification of Letters Patent.

Patented Oct. 21, 1919.

Application filed February 8, 1917. Serial No. 147,449.

To all whom it may concern:

Be it known that I, EDWIN M. WINTERBOURNE, a citizen of the United States, and a resident of Trinidad, in the county of Las 5 Animas and State of Colorado, have invented a certain new and useful Improvement in Kitchen Work-Stools, of which the following is a specification.

The present invention relates to furniture, 10 and has particular reference to improvements in chairs or stools.

An object of the present invention is to provide a stool which may be used in the kitchen; which may be constructed substantially 15 entirely of metal; which is of sanitary construction; which is light in weight and easily handled; which is provided with a novel form of seat embodying cushioning features; which is strong and durable; and 20 which is provided with an adjustable and resilient back.

Another object of the present invention is to provide a stool or chair with a seat of novel construction which may be formed of 25 a frame or body portion in the nature of a casting, and with a seat portion or covering member formed of pressed steel or other suitable material which is resilient or flexible, the frame being so formed as to support 30 the seat portion and admit of the flexing of the same.

The above, and various other objects and advantages of this invention will be in part described, and in part understood from the 35 following detailed description of the present preferred embodiment, the same being illustrated in the accompanying drawings wherein:

Figure 1 is a side elevation of a stool or 40 chair constructed according to the present invention, parts of the same being shown in section.

Fig. 2 is a top plan view of the same, parts being broken away for the sake of clearness.

Fig. 3 is a detail view taken through the 45 lower portion of the adjustable back, showing the same in transverse central section.

Fig. 4 is a fragmentary sectional view of the rear portion of the seat, disclosing a 50 modified form of mounting for the back.

Referring to this drawing, the base portion of the chair or stool comprises a plurality of legs 10 of any suitable configura-

tion, and which are preferably constructed of tubular metal. The legs 10 converge upwardly and are welded or otherwise suitably secured in the sides of a supporting block 11. The supporting block 11 is in the form of a casting having a relatively large screw-threaded vertical opening there-through. The lower ends of the legs 10 are suitably braced by means of a foot rail 12 of tubular construction which is of ring form, and which is riveted or otherwise secured to legs 10 adjacent to the lower ends. 55 The legs 10 are provided upon their lower ends with pads or the like to support the chair or stool.

The seat portion of the stool comprises a body part or base member 13 which is in 60 the form of a casting of substantially T-shape, the opposite sides of the stem of the casting converging forwardly, while the ends of the head thereof converge rearwardly. The opposite lateral edges of the stem of 65 the base member 13 are preferably concaved or dished, as at 14, and the upper face of the base member 13 is depressed or concaved, as at 15.

A seat post 16, in the form of a jack-screw, 70 is secured to the lower intermediate portion of the frame 13 and projects downwardly, and is adapted for threaded engagement through the supporting block 11 of the base. By turning the screw 16 the seat 75 frame may be raised and lowered to adjust the stool to the desired height.

A seat 17, preferably in the form of a 80 pressed steel sheet, is secured over the frame 13 and conforms substantially to the marginal formation of the frame 13. The intermediate portion of the seat 17 is slightly 85 depressed and is adapted to flex into the concavity 15 when in use to provide a cushion seat. A depending reinforcing and attaching flange 18 is formed at the marginal edge of the seat 17 and engages the front 90 end of the stem and the rearwardly inclined side edges of the head of the frame 13 and may be secured thereto by screws 19 or the like. 95

The frame 13, and the seat 17 are provided intermediate their ends with rearwardly converging sides forming rear lateral edges, the same being relatively short as compared 105 with the forwardly converging lateral edges.

The forward lateral edges 20 of the seat 17 are preferably spaced from the concaved edges 14 of the frame 13 to provide lateral portions of the seat 17 which have substantially no support, except for the inherent stiffness of the pressed steel and the formation of the flange 18. Such a construction not only permits of the desired flexing of the forward lateral edges of the seat 17, but also provides a casting or base member 13 which is relatively small and light in weight.

The rear laterally enlarged portion of the seat frame 13 terminates in a transversely extending straight edge 21, and the latter may be provided with a pair of widely spaced-apart rearwardly extending lugs 22 and 23, between which is arranged a drum or spool 24. The drum or spool 24 is supported upon a combined pivot and clamping bolt 25 having the head 26 thereof rounded at its marginal edge and enlarged to provide a journal mounted for rotation in the lug 22. The lug 23 is provided upon its inner face with serrations or teeth 27 adapted to engage the correspondingly formed serrations or teeth 28 on the adjacent end of the drum or spool 24. A clamping nut 29, preferably of the wing type, is threaded upon the reduced end of the bolt 25 and is adapted to engage against the outer side of the lug 23. The head 26 engages the smooth end of the drum 24 and is adapted to draw the latter against the lug 23 when the clamping nut 29 is tightened.

The back frame is formed of a single length of relatively heavy wire 30 which is returned upon itself to provide a loop 31, which engages about a projection 32 formed on the peripheral surface of the drum 24 intermediate the ends thereof. The opposite sides or arms of the wire 30 are diverged for a short distance from the loop 31, and are wrapped spirally about the drum 24 and are projected tangentially therefrom near the opposite extremities of the drum. The drum 24 may be turned between the lugs 22 and 23 to project the wire 30 upwardly at the desired angle with respect to

the seat. A rest 33 is adjustably mounted upon the upper ends of the wire 30 by means of a clamp 34.

In Fig. 4 there is shown a modified mounting of the body wire or frame 30^a of the back upon the seat. The lower ends of the wire 30^a are turned forwardly to provide shanks 31^a adapted to project into socket openings 34^a formed in the rear edge 21 of the seat base member 13, and are clamped in adjusted position in the socket openings 34^a by means of set-screws 25^a carried by the seat frame 13.

From the above description it will be readily seen that the stool of this invention is constructed entirely of metal, that it comprises but relatively few parts, and that the relatively large base member 13 is so formed as to reduce the weight thereof and to provide a construction using a relatively small amount of material. The peculiar formation of the frame 13 also resiliently supports the seat 17 and at the same time suitably braces the same against undue flexing or cramping.

It is of course understood that various changes and modifications may be made in the above-specifically described stool without departing from the spirit of this invention, and being restricted only by the scope of the following claim.

I claim:—

In a stool, the combination, of a base member substantially T-shaped in plan with its stem forward and the lateral faces of its head converging rearwardly, a back rest supported from the back of the head of said base member, and a seat of pressed sheet metal formed to provide a saddle and a downwardly projecting flange, extending along the margin of the saddle except at the back thereof, said flange lying in surface contact with the base of the stem and the said lateral faces of the head of said base member, but free of said back rest, to maintain the saddle against shifting movement on said head.

EDWIN M. WINTERBOURNE.
